WINDOW CONSTRUCTION

Oscar H. Johnson, Chicago, Ill.

Application October 11, 1945, Serial No. 621,786

4 Claims. (Cl. 189—75)

1

This invention relates to improvements in sash guides and weather seals for window sash.

One of the objects of the invention is to provide sash guides particularly designed to facilitate the installation and removal of window sashes.

Another object of the invention is to provide improved sash guides which afford a wood to metal contact on the sliding surfaces, in a construction which may readily be assembled or disassembled.

Another object of the invention is to provide metal sash guides constructed for ease of assembly with the window sashes and with the window frames in which they are to be placed, to decrease the time required for installing windows, and yet provide a window construction which has excellent weather-proofing characteristics.

Numerous other objects and advantages of the invention will be particularly pointed out hereinafter or will become apparent from a reading of the specification and upon reference to the drawings.

In the drawings:

Figure 1 is a horizontal sectional view looking downwardly, taken at a level about midway of the upper sash, in a window construction made in accordance with this invention;

Figure 2 is a sectional view at the same level showing a step in the removal or installing of the lower inner sash;

Figure 3 is a sectional view again at the same level showing a step in the removal or installing of the upper and outer window sash;

Figure 4 is a disassembled perspective view of portions of the vertical members employed for guiding the sashes, turned over into a horizontal plane, in this view;

Figure 5 is a vertical sectional view through a window assembly made in accordance with the invention showing particularly the weather striping provision at the bottom of the inner and lower sash.

Figure 6 is a vertical sectional view on a reduced scale of the top portion of a window constructed in accordance with this invention.

Referring further to the drawings, at the opposing sides of the window frame there are provided the following assemblies of metal parts. One strip of metal rising vertically at the right side of the window frame is generally designated as A and includes a flat slideway 1 for the inner sash provided at vertical intervals with holes such as 2 and a U-shaped channel portion 3,

2

which fits snugly into a groove 4 provided in the vertical window frame member 5.

Beyond the channel 3 toward the outside of the window is another flat slideway 6 which terminates at a folded flange 7, outside of which the strip is folded back upon itself providing a channel between the surfaces 8 and 9 into which the screen guide or retaining strip is fitted, as will be better understood by reference to Figures 1 to 3 inclusive. The flange 7 serves as the outside guide for the upper sash.

The screen guide or retainer is the structure generally indicated as B in Figure 4 and has two portions 10 and 11 which interlock with the portions 8 and 9 of the strip A, with the outside retaining flange 12 folded back upon itself, as illustrated. The frame of the screen is indicated as 13 in Figure 1.

As is apparent in Figure 1, the strip C at the 20 left side of the window frame is identical with the right hand strip A, as thus far described. However, as will be explained later, one has an integral inside guide for the inner sash, while the other has a separable inside guide. The 25 screen retainer D is similar to B.

The vertical metal strips A, B, C, and D are assembled and inserted into the window frame members 5 and 14, and are secured therein by nails, screws, or in any other suitable manner.

30 Thereafter, the upper sash 15 will be inserted until it occupies the position shown in Figure 2. Next, the parting strips 17 and 16, which are folded strips of metal having considerable resilience which tends to spread their vertical legs 35 apart, are inserted into the channel 3 in the vertical metal strip A, and into the corresponding channel in strip C. These parting strips hold the sashes snugly against the opposing guide flanges, yet permit them to slide freely

40 from the top to the bottom of the window frame. The resilient legs on the parting strips, bearing on the insides of the channels 3, prevent any passage of air therethrough, and thus serve also as weather strips.

45 The lower sash 18 may now be inserted, in the manner indicated in Figure 2, until it occupies the fully inserted position of Figure 1. Thereafter, a removable strip, generally indicated as E, having one leg 19 for contacting the vertical inner 50 surface of the lower sash and another leg 20 which may be inserted between the section 2 of the guide A and the adjacent surface of the window frame 5, is inserted until it occupies the position shown in Figure 1. After it is in place the screws 21, which had previously been loosened,

will now be tightened, thus locking the section 2 against section 20 which will hold the part E firmly in place. The screws 21 may be spaced at any desired intervals to pass through holes 2 in the guide member A and through V-shaped notches 22 provided in the guide E. Thus when the screws are slightly loosened, the member E may easily be withdrawn. By running the inner or lower sash up or down access to all of the screws is easily obtained.

The integral flange 23 on the vertical sash guide C shown at the left of Figure 2 cooperates with the resilient parting strip 16 to snugly guide the inner sash.

Preferably, the removable guide E and the permanent guide 23 will extend the full height of the window frame in order to provide a uniform guide for the inner sash all the way to the top of the window and to afford a uniform appearance. The removable part E, however, is easily removed simply by the use of a screw driver, while the parting strips 16 and 17, after the inner sash has been removed, are easily pulled out either with the fingers or with a pair of pliers. Thus it will be appreciated that without any unusual equipment in the way of tools, both sashes may be removed or reinserted with great ease, and yet when they are reassembled and locked in position the entire assembly affords an excellent weather proof construction with metal-to-wood sliding contacts for both sashes.

Referring now to Figure 5 the construction at the bottom of the window frame is exceedingly simple, it being sufficient to provide only a single strip of metal extending across the bottom of the frame, this element being generally designated as F and being shaped as indicated to provide one flange 24 which faces against the bottom window frame member 25, the folded section 26 upon which the screen sash 13 may rest, a middle section 27 located as indicated at the bottom of the sash slideways, and an upwardly extending folded flange 28 which is adapted to extend into a groove 29 provided in the lower sash 18. A folded section 30 on the part F completes the horizontal surface on which the bottom of the inner sash rests. The folded flange 28 and the groove 29 in the sash contribute to the weather stripping of the entire assembly. Of course when the inner sash is being removed it is first lifted off the flange 28.

Figure 6 shows how the top of the window construction is finished to cooperate with the parts heretofore described to provide a neat, weather proof construction. A single metal plate extends across the top of the window frame, being generally designated by the letter G, and has a downwardly extending flange 31 adjoining a horizontal section 32. A channel 33 is formed therein similar to the channel 3 and extends into a corresponding groove, not shown, in the adjoining top member of the window frame. A horizontal section 34 and a downwardly extending flange 35 complete the metal construction at the top of the window. I provide a folded metal insert 36, similar to the folded parting strip 17, to fit snugly into the channel 33, preventing the upper edge of the outer sash from rattling and holding it snug and in a weather proof relationship. The insert 36 may be made removable or not, as desired. It does not require removal during the insertion or removal of the upper sash, for it will be apparent that the upper sash may be lowered before removal sufficiently to clear the insert 36.

In view of the narrowness of the parting strips

16 and 17 only a narrow ledge 37 need be provided on the inner sash to effect a tight seal with the lower margin of the outer and upper sash, as shown in Figure 6.

5 The construction herein shown and described is easily coordinated with a wooden box frame for the window, as is indicated in the drawings. Obviously a metal frame may be used instead of a wooden frame.

10 Although I have shown and described one particular embodiment of my invention, I do not desire to be limited to the exact details of construction herein shown and described. It should be understood that the invention comprehends all 15 variations and modifications within the scope of the appended claims.

I claim as my invention:

1. Sash guides for embracing opposite margins of inner and outer sliding sashes comprising a sheet of metal adapted to be vertically positioned in each of the opposing vertical margins of a rectangular window frame, each sheet of metal having parallel slideways for the inner and outer sashes, a right-angle flange at the outside margin of the outer slideway in each sheet forming a lateral outer guide for the outer sash and an inner guide for a screen frame, a narrow channel in each vertical sheet between said slideways extending laterally outside the plane of said sash slideways for interfitting with a groove in a vertically grooved window frame, removable, laterally expansible, metal parting strips inserted into said channels, consisting of strips of metal bent upon themselves to form adjacent resilient legs, the inner sash slideway at one side of the window frame 20 having an integral right-angle extension constituting an inner lateral guide for the inner sash, and a removable vertical strip of right-angle transverse cross section having one right-angle leg overlapping the inner sash guideway at the other side of the window frame, and its other leg 25 providing an inner lateral guide for the inner sash, and means for releasably securing the last said strip to said inner sash guide and a surrounding window frame in said overlapping position.

2. Vertical sash guides for a window having two sliding sashes, comprising a sheet of preformed metal for each of the opposing vertical sides of the window frame, each sheet having a flange thereon to constitute an outside guide for the outer sash, two parallel surfaces in each sheet 30 constituting slideways for the outer and inner sashes, and separated by a U-shaped channel extending laterally outside the plane of said sash slideways for interfitting with a groove in a vertically grooved window frame, an integral flange on one said sheet forming the inner guide for the inner sash, a removable flange constituting an inside guide for the inner sash, said guide being detachably connectable to the other preformed 35 sheet, means in the inner slideway of said other sheet for securing said removable flange to said inner slideway in operative position, and a pair of resilient metal parting strips inserted into said U-shaped channels at opposite sides of the window for yieldably pressing the two sashes against their adjoining outer and inner guides and providing a weatherproof seal between the sashes and the parting strips.

3. In combination with vertical sash guides as set forth in claim 2, a member adapted to be placed in the top of the window frame to cooperate with the upper ends of both sashes and having a cross section transverse to its length identical with the transverse cross section of the 40 first described vertical sash guide, and a U-shaped

resilient metal parting strip inserted into the upwardly extending channel in said top member.

4. Vertical sash guides comprising two pre-formed metal sheets for positioning at opposite vertical margins of a rectangular window frame, each sheet having an integral flange serving as an outer lateral guide for the outer sash, a vertical U-shaped channel in each sheet extending laterally outside the plane of said slideways for interfitting with a groove in a vertically grooved window frame, a laterally expansible removable metal parting strip for each channel, inner and outer sash slideways in each sheet on opposite sides of said channel, one sheet having an integral flange constituting an inner guide for the inner sash, a removable metal strip of transverse right angle cross section having one leg constituting an inner guide for the inner sash and its other leg being inserted between the inner sash slide-

way of the other sheet and the window frame, and means releasably locking said latter strip in operative position.

OSCAR H. JOHNSON.
